[57] CLAIM

The ornamental design for a toy vehicle, as shown and described.

DESCRIPTION

FIG. 1 is a side elevational view of a toy vehicle, showing my new design, the side opposite being a mirror image;
FIG. 2 is a top plan view thereof;
FIG. 3 is a front elevational view thereof;
FIG. 4 is a rear elevational view thereof;
FIG. 5 is a bottom plan view thereof;
FIG. 6 is a side elevational view with certain components shown in a different position from that shown in FIG. 1; and,
FIG. 7 is a top plan view thereof.

*FIG. 1.**FIG. 2.***FIG. 3.****FIG. 4.****FIG. 5.***FIG. 6.**FIG. 7.*
